UNITED STATES PATENT OFFICE

PAUL N. ELDERKIN, OF LOS ANGELES, CALIFORNIA

LUBRICANT AND CARBON REMOVER

No Drawing.

Application filed April 6, 1929. Serial No. 353,264.

This invention relates to compositions of matter and more particularly to compositions for cleaning, lubricating and otherwise treating and conditioning the working surfaces of 5 cylinders, pistons, valves, valve seats and all surfaces directly affected by the heat of combustion or subject to deposition of products of combustion.

It is the object of this invention to provide a composition of matter of this character which may be readily introduced within the motor cylinder, preferably in fluid form, and distributed over the surfaces to be treated and conditioned, and which will be 15 superior in point of inexpensiveness, facility of handling and introduction into cylinders, safety in storage, handling and use, freedom from deterioration, and general effectiveness and efficiency in service.

With the above objects, together with others that will appear, the invention consists in the novel and useful provision, association and action and effect of ingredients and substances entering into the composition, and of 25 the composition, all as hereinafter described and finally pointed out in claim.

In practicing the invention in a preferred manner, and in the utilization of acceptable and preferred ingredients and substances in 30 admixture, and preferably in liquid form, I provide a carbon remover and carbon bond solvent such as trichlorethylene and acetone, a lubricant, preferably any light mineral oil, and a thinner for the lubricant, such as 35 Eocene. Eocene is a petroleum product of the illuminant group lying between kerosene and signal oil in the petroleum series and has slow burning properties. The carbon which becomes deposited upon the interior cylinder 40 surfaces, pistons and valves and valve seats and other parts reached by the products of combustion in internal combustion motors, is understood to include both crystalline carbon and amorphous carbon, the latter mixed 45 with a heavy petroleum residue of the fuel bonding together the carbon crystals, and thus acting as a binder. I have found that the acetone and trichlorethylene act as a ready solvent for such residue in the carbon 50 bond. In their combined action I find that

a highly effective removal of all the carbon occurs. The Eocene, which is a lubricant, acts to dilute the lubricating oil and to increase the bulk thereof, so that this component part of the compound increases the effectiveness of lubrication of the parts of the motor to which it has access. 55

The cleaning or conditioning factors or elements of the composition, to-wit: carbon bond solvents, coact with the lubricating ingredients last mentioned, and in removing the carbon deposits they provide a bright clean surface for reception of the lubricant and its effective functioning in the coaction of the pistons, cylinders and valves and valve 60 seats. So that all of the ingredients produce a highly efficient ultimately unitary effect. 65

While it might be possible to obtain approximately satisfactory results in the employment of but one of the solvents mentioned 70 and in the employment of the lubricant mentioned without the thinner therefor, I find that better results are obtained in the provision of all of the kinds of ingredients 75 mentioned.

These ingredients are preferably commingled, as fluids, in substantially the following proportions, to-wit: in a total volume of 55 gallons, 40 gallons of Eocene, 12½ gallons of light mineral oil, 1½ gallons of 80 trichlorethylene and 1¼ gallons of acetone. Of course, material variations may be made from these relative quantities of the ingredients without departing from the invention, and similarly, within the invention, variations and substitutions of materials and substances having qualities akin to those of the specified materials may be made. 85

The composition of matter, in its fluid form, may be injected or introduced within the cylinder through the intake valve with the carburetted mixture, and readily distributes itself over the surfaces of the cylinder, piston, valves and valve seats and all surfaces subjected to heat in the operation 90 of the motor. The carbon and carbon bond removed by the solvents from the surfaces, is discharged from the motor through the exhaust valve with the products of combustion and gases incident to burning of the ex- 95 100

plosive mixture, and the lubricant covers the cleaned and brightened surfaces from which the carbon has thus been removed and discharged. Thus, thorough cleaning and conditioning of the surfaces of the thermally affected working parts of the internal combustion motor take place and are affected during the normal operation of the motor and without taking the same down or discontinuing service. The composition is introduced into the motor in the manner specified at appropriate intervals of time, or whenever indication, by tests or otherwise, denote the necessity for such cleaning and conditioning and lubricating.

Having thus disclosed my invention, I claim and desire to secure by Letters Patent:

A composition of matter, including a light mineral oil, a thinner for the mineral oil, trichlorethylene and acetone, in admixture, substantially in the proportions by volume of 40 parts Eocene, 12½ parts of mineral oil, 1¼ parts trichlorethylene and 1¼ parts acetone.

In testimony whereof I have signed my name to this specification at Los Angeles, Calif., this 30th day of March, 1929.

PAUL N. ELDERKIN.
